SHOE HEEL

John B. Snizek, Detroit, Mich.

Application September 28, 1949, Serial No. 118,229

1 Claim. (Cl. 36—36)

1

My invention relates to a new and useful improvement in a shoe heel adapted for attaching to shoes, and particularly relates to that class of shoe heel which is made from a pair of sections.

One of which is permanently attached to the shoe and the other of which is detachably engaged by the sections.

It is an object of the present invention to provide a shoe heel of this class having an upper section and a lower section, the upper section being secured to the shoe, and the lower section having a plurality of projections or bosses which engage in openings formed in the upper section for securing the two sections together.

It is another object of the invention to provide a heel embodying a pair of sections one of which has openings, the other having bosses and in which the bosses are slightly larger in diameter than the openings.

Another object of the invention is the provision of a heel of this class having an upper section and a lower section, the lower section being secured to the upper section by bosses mounted thereon which project into openings formed in the upper section and in which the lower section has an inclined face engaging the opposed face of the upper section which straightens out upon being mounted in position so as to provide a vacuum seal.

Another object of the invention is the provision of a heel having an upper section and a lower section formed from rubber or the like and in which the lower section has its peripheral edge inclined to the plane of the heel proper so that when the two sections are mounted together, the peripheral edge of the lower section will align with the peripheral edge of the upper section.

Other objects will appear herein.

Forming a part of this specification are drawings in which,

Fig. 1 is a side elevational view of a fragment of a shoe showing the invention attached, the invention being shown in sections.

Fig. 2 is a perspective view of the upper section of the heel attached to a shoe.

Fig. 3 is a perspective view of the lower section of the heel,

Fig. 4 is a fragmentary sectional view showing the parts in separated relation with the upper part mounted on a fragment of a shoe.

In the drawings I have shown a fragment of a shoe 8 having the heel supporting portion 9 to which is secured a rubber upper section 10 of a heel. Formed in this section 10 are spaced

2

apart openings 11 which are spaced inwardly from the perimeter of the heel section. The openings 12 are formed for reception of securing means 17 and it will be noted that these openings 12 are positioned inwardly of the outer edge of the openings 11. The lower section 13 of the heel is provided with the spaced apart projections or bosses 14 which are adapted to enter the openings 11. As shown in Fig. 1 these bosses 14 are of less length than the thickness of the heel section 10 so that there is a space in the opening 11 at the upper or inner end of the boss 14. As shown in Fig. 4, the diameter of the bosses 14 is slightly larger than the diameter of the openings 11 and, the opposed face 15 of the heel section 13 adjacent to the bosses 14 is inclined to the main plane of the heel section 13. It will also be noted that the perimeter 16 of the heel section 13 is inclined to its plane.

When the upper section 10 is secured by the nail 17 to the heel supporting portion 9 of the shoe 8, the openings 11 will be projected outwardly beyond the outer part of the nail. Consequently, a part of the heel and a part of the openings 11 in the heel section 10 are positioned outwardly beyond the nails so that a twisting or bending of the edge of the heel supporting section 10 will not disturb the nails 17 and cause them to pull loose. After this upper section 10 has been fastened in position, the lower section is mounted on the upper section by forcing the resilient, yieldable bosses or projections 14 into the slightly smaller openings 11. In this operation, these bosses are placed under strain and distorted out of their natural shape and size so that they form a sealing contact with the opening 11. At the top of the opening there is a space in which air is imprisoned thus forming a cushion. Due to the fact that the members 14 tightly seal the openings 11, air cannot enter the openings 11 and consequently, the removal of the section 13 is prevented. The section 13 can, however, be removed by further distorting and lengthening the projections or bosses 14. Consequently, these

bosses must be flexible and stretchable. As the inclined face 15 is brought into engagement with the opposed face of the section 10, this inclined face is straightened out by shoving the bosses or projections 14 inwardly a sufficient distance and by straightening out this inclined face, a tight seal between the opposed faces of the two sections 10 and 13 is effected so that air cannot enter between these sections thus further resisting any undue removal of one section from the other. Experience has shown that it is necessary

to form the perimeter 16 inclined as shown in Fig. 4, so that when the section 13 is mounted on the section 10 as shown in Fig. 1, this perimeter 16 will register with the perimeter of the upper section 10. With this inclined face not present, the perimeter of the lower section 13 would incline inwardly from the perimeter of the upper section 10.

A heel constructed and mounted in this manner is one which has proven most efficient in use. It is durable, easily and quickly attached and may be easily and quickly detached when the lower section 13 becomes worn.

What I claim is:

A heel construction of the class described comprising an upper section and a lower section, said upper section being adapted for attaching to the shoe and having a plurality of spaced apart openings extending around and positioned inwardly of the perimeter thereof; said openings being of constant diameter from end to end; a plurality of cylindrical projections extending outwardly in spaced relation to each other from one face of said lower section, and of slightly greater diameter than the openings in said upper section and formed from yieldable, stretchable material and insertable into said openings for securing said lower section on said upper section, the face of said lower section opposing the face of said upper section being inclined around said pro-

jections prior to entry of said projections into said openings and, upon entry of said projections into said openings, lying flat in engagement with the face of said upper section, the perimeter of said lower section being inclined outwardly and downwardly from its upper face prior to mounting on to said upper section and adapted upon mounting on said upper section to be distorted to be in alignment with the perimeter of said upper section and said cylindrical openings being longer than said projections whereby air cushion pockets are provided at the upper ends of the projections.
